Warren W. House,
his ATTORNEY

UNITED STATES PATENT OFFICE.

RALPH A. MEGENITY, OF KANSAS CITY, MISSOURI.

CONCRETE CONSTRUCTION.

Application filed February 4, 1919. Serial No. 274,891.

To all whom it may concern:

Be it known that I, RALPH A. MEGENITY, a citizen of the United States, residing at Kansas City, in the county of Jackson and 5 State of Missouri, have invented a certain new and useful Improvement in Concrete Constructions, of which the following is a specification.

My invention relates to improvements in 10 concrete construction.

One object of my invention is to provide novel, simple, cheap and efficient means for securely attaching veneer facings to cementitious bodies, such as walls, ceilings, piers, 15 columns, beams, posts, lintels and the like.

My invention provides further a novel metal stud, which is durable, cheaply manufactured, which can be easily and quickly attached to a mold, which can be readily 20 and easily utilized for attaching a veneer facing to a wall, ceiling or other cementitious body, which will be retained securely in such cementitious body, and which permits of the attachment thereto at any point 25 along its length of a wall or ceiling tie.

My invention provides further novel means for supporting facing material to a ceiling composed of cementitious material.

The novel features of my invention are 30 hereinafter fully described and claimed.

In the accompanying drawing, which illustrates my invention,

Fig. 1 is a perspective view, partly broken away, showing my improved anchoring 35 member attached to a form and to a concrete wall.

Fig. 2 is a perspective view, enlarged, of one form of my improved anchoring member.

Fig. 3 is a plan view of a wall tie adapted 40 to be used in connection with my improved anchoring member.

Fig. 4 is a vertical sectional view of my improvement as applied to a ceiling.

Fig. 5 is a perspective view of a modified 45 form of my improved anchoring member.

Similar reference characters designate similar parts in the different views.

Referring to the form of my invention 50 shown in Figs. 1, 2 and 4, 1 designates a substantially straight strip, preferably sheet steel, which is folded upon itself to form a longitudinal row of laterally extending anchoring arms 2, having lateral extensions 3, 55 each anchoring arm being preferably a loop

having its opening extending transversely so as to receive therein cementitious material. The anchoring arms 2 extend laterally from one side only of the body of the strip 1 and, preferably, converge outwardly, so that the 60 arms form a dove-tail connection with the concrete, the concrete between the arms and also outside of the arms serving to hold the arms firmly in the wall.

For attaching the anchoring member to 65 the inner side of a wall form 4, any suitable means may be employed. For effecting this function, I have shown the strip 1 as having stamped from its body a plurality of securing devices preferably comprising pointed tongues 5 which are cut from the body of the strip 1 and extend laterally from the opposite side of the strip, as best shown in Fig. 2.

In applying my approved anchoring 70 member to a concrete wall, the strips 1 are attached in a vertical position to the inner side of the wall form 4, the tongues 5 being driven into the form, as shown in Fig. 1.

The concrete 6 is then poured into the 75 form, thereby embedding the strips 1 in the concrete with the outer sides of the strips flush with the adjacent side of the wall. The cementitious material fills the openings through the anchoring arms 2.

After the concrete has sufficiently hardened, the mold boards 4 are removed. The veneer facing 7 is then laid in horizontal layers to a height at which it is desired to bond it to the wall. The wall ties 8, each of 80 which is provided at each end with a hook 9, are then hooked about the strips 1 and laid upon the upper layer of the veneer facing 7, as shown in Fig. 1, sufficient material 85 being gouged from the wall to permit one set of hooked ends of the wall ties being passed around the anchoring members, or the latter may be pried out from the wall sufficiently to enable the hooks to pass between the strip and the wall.

The laying of the veneering 7 is then continued until it reaches a height at which it is desired to again bond it to the wall 6, at 90 which time another set of wall ties 8 are laid on the top row of the facing and attached, as already described, to the strips 1.

With my improved anchoring member, the wall ties can be attached at any desired height.

In utilizing my improvement for suspend- 110

ing ceiling material from a horizontal concrete or cementitious ceiling body 10, the strips 1 are embedded in the body 10 in a horizontal position with the lower sides of the strips 1 flush with the lower side of the body 10 and with the anchoring arms 2 embedded in the body 10.

Vertical tie members 11 each provided with a hook 12 at its upper end, have said hooks embracing the strip 1, as shown in Fig. 4. The horizontal ceiling material 13 is then attached in any desired manner to the lower ends of the tie members 11, the under side of the body 10 being gouged out at the proper places to permit the passage of the hooks 12 between the body and the strip 1.

In the form of my invention shown in Fig. 5, the strip 14, preferably flat sheet metal, is folded upon itself to form a longitudinal row of anchoring arms 15, which all extend laterally from one side of the strip 14 and which at their inner ends are bent at right angles to form lateral extensions 16, which prevent the anchoring arms 15 from being pulled from the wall or ceiling to which the strip 14 is attached in the manner described with reference to the anchoring member 1.

The strip 14 may have punched from it on the side opposite to the arms 15 a plurality of pointed tongues 17, corresponding to the tongues 5 in function and mode of operation. It will be noted that the anchoring arms 2 and 15 are each formed by folding the metal strip its full width upon itself, which obviates the slitting or cutting of the metal and the use of dies for thus purpose, and affords a maximum of strength and holding power in the arms.

I do not limit my invention to the structures shown and described, as various modifications, within the scope of the appended claims, may be made without departing from the spirit of my invention.

What I claim is:—

1. An anchor strip of the character described, consisting of a metal strip alternate sections of which form respectively longitudinally extending portions adapted to lie along the surface of the concrete structure and anchoring arms adapted to be embedded in a concrete structure, the anchoring arms extending laterally from the longitudinally extending portion and having portions extending in a direction transverse to the length of the arm to provide anchor parts, said anchoring arms serving to connect the longitudinally extending portions, which latter are otherwise separate from each other, substantially as described.

2. An anchoring member of the character described, consisting of a sheet metal strip conformed to provide straight unfolded portions adapted to lie flat against a form, and folded portions, folded out of the plane of the unfolded portions, constituting anchor arms each projecting laterally to one side from the adjacent ends of adjoining unfolded portions, and serving as the sole connection therebetween, said anchor arms having parts extending substantially parallel to the unfolded portions.

3. A wall tie of the class described, comprising a flat strip of metal of uniform width and cross-section doubled upon itself at intervals along its length so as to provide a plurality of anchor parts equal in width to said strip, all disposed on one side of the strip transversely thereto and with the two leg portions of each anchor part pressed together, said anchor parts having the doubled over ends thereof enlarged and being adapted to be embedded in a wall or the like so as to locate said strip on the face thereof.

In testimony whereof I have signed my name to this specification.

RALPH A. MEGENITY.
